CLAIM

The ornamental design for a sports bra as shown and described.

DESCRIPTION

FIG. 1 is a front perspective view of a sports bra in accordance with my new design;

FIG. 2 is a front view of the sports bra of FIG. 1;

FIG. 3 is a rear view of the sports bra of FIG. 1;

FIG. 4 is a right side view of the sports bra of FIG. 1; and,

FIG. 5 is a left side view of the sports bra of FIG. 1.

The broken lines in the figures depict unclaimed features that form no part of the claimed design.

1 Claim, 5 Drawing Sheets
